TYPEWRITER

Chester J. Abend, Camillus, James J. Bienkowski, Cazenovia, and John E. Jolliffe, Manlius, N.Y., assignors to SCM Corporation

Filed Dec. 8, 1972, Ser. No. 313,203

Term of patent 14 years

Int. Cl. D18—01

U.S. Cl. D64—11 A

FIG. 1

FIG. 2

FIG. 1 is a front perspective view of a typewriter showing our new design;

FIG. 2 is a top plan view;

FIG. 3 is a front elevational view;

FIG. 4 is a right side elevational view;

FIG. 5 is a left side elevational view; and

FIG. 6 is a rear elevational view.

The typebar guide and typebars are conventional and have been omitted for ease of illustration.

We claim:

The ornamental design for a typewriter, as shown and described.
